(57) **CLAIM**

The ornamental design for a motor transportation fixture, as shown and described.

DESCRIPTION

FIG. 1 is a left upper perspective view of a motor transportation fixture according to the present design;
FIG. 2 is a front elevational view of the fixture;
FIG. 3 is a rear elevational view of the fixture;
FIG. 4 is a top plan view of the fixture;
FIG. 5 is a bottom plan view of the fixture; and,
FIG. 6 is a left side elevational view of the fixture, the right side view being a mirror image thereof.
